UNITED STATES PATENT OFFICE.

PAUL H. QUALMANN, OF MILWAUKEE, WISCONSIN.

SELF-FILLING FOUNTAIN-PEN.

1,381,332.

Specification of Letters Patent. Patented June 14, 1921.

Application filed June 1, 1920. Serial No. 385,445.

To all whom it may concern:

Be it known that I, PAUL H. QUALMANN, a citizen of the United States, residing at Milwaukee, county of Milwaukee, and State 5 of Wisconsin, have invented new and useful Improvements in Self-Filling Fountain-Pens, of which the following is a specification.

This invention relates to self filling fountain pens.

Self filling fountain pens as usually made have the disadvantage that they require the use of both hands for their manipulation during the filling operation. This is often 15 inconvenient as it is sometimes desirable to fill the pen while one hand only is available for such purposes. It is therefore an object of this invention to provide a self filling fountain pen which may be readily manipulated by one hand of the operator leaving 20 the other hand free.

Other objects of this invention are to provide a self filling fountain pen which may be operated in a convenient manner from 25 the end of the pen as distinguished from a fountain pen which has to be filled by manipulation of a lever at the side of the pen, and to provide locking means for locking the operating mechanism against accidental 30 motion.

Other objects are to provide a self filling fountain pen of extreme simplicity which may therefore be made at minimum cost; to provide a self filling fountain pen which 35 is composed of a minimum number of parts; and to provide a self filling fountain pen in which the tube is collapsed throughout its entire length thereby producing a maximum filling of the pen.

40 In the drawings:

Figure 1 is a longitudinal view partly in section of the fountain pen showing the tube in expanded position.

Fig. 2 is a similar view showing the tube in 45 collapsed position.

Fig. 3 is a detail of the spring arms and bearing plates.

Fig. 4 is a sectional view of the cap for the upper end of the fountain pen.

50 Fig. 5 is a section on the line 5—5 of Fig. 1.

The end cap which is used to cover the pen point when not in use has been omitted from the drawings for the sake of clearness.

The body 1 of the pen is provided with a 55 tapered opening 2 in which the tapered end member 3 has a forced fit. This tapered end member 3 carries the pen point and asso-

ciated parts. The tapered end member terminates in a shoulder 4 and a nipple 5 upon which latter is secured the collapsible 60 tube 6. The upper end of the body 1 is closed by means of a cap 7 which has threaded engagement with the body portion 1. The cap 7 carries a thumb operated plunger 8 which projects outwardly through 65 an opening 9 in the cap under normal conditions. The plunger 8 has an enlarged cylindrical portion 10 upon its inner end which slides within the cylindrical inner portion of the cap 7 and in its outward position 70 seats upon the shoulder 11 of the cap 7. This portion 10 carries a pin 12 which seats within a bayonet slot 13 when in extended position. When it is desired to press the plunger inwardly, it is given a partial turn 75 so that the pin 12 moves first in the horizontal portion of the bayonet slot and finally arrives in the vertical portion of the bayonet slot. In this position, the plunger is adapted to be pressed inwardly by the thumb of 80 the operator.

The mechanism for transforming the longitudinal motion of the plunger 8 into the lateral motion for collapsing the tube 6 comprises a pair of spring arms 14 which 85 extends substantially the full length of the body of the pen, the free ends 15 seating against the shoulder 4, and the yoke portion 16 being positioned adjacent the enlargement 10 of the plunger 8. These spring 90 members 14, it will be noted from Fig. 1, are bowed inwardly to a slight extent in normal position so that any pressure exerted longitudinally of the pen tending to shorten the distance between the yoke 16 and the 95 ends 15 results in causing the approach of the central portions of the spring arms 14 as shown in Fig. 2. This motion of the spring arms 14 clamps the tube 6 between them, but such clamping action, if applied 100 directly to the tube, would be over only a limited area of the tube. In order to enhance the effect of this clamping action, a pair of rigid plates 17 are positioned one upon each side of the tube and are arranged 105 to extend substantially the entire length of the tube, thereby causing the tube to be contracted throughout substantially its entire length. These plates 17 are held in position upon the spring arms 14 by means 110 of a pair of ears 18 formed integrally with the plates and bent about the spring arms 14 adjacent the central portion thereof.

The locking action secured by the co-

operation of the pin 12 and the bayonet slot 13 is effective against a longitudinal accidental motion of the plunger 8. However, to guard against an accidental twisting motion 5 of the plunger 8 which would disengage the pin from the horizontal portion of the bayonet slot, additional means are provided as shown in Fig. 4. The horizontal portion of the bayonet slot is provided with an enlargement 19 which is in the nature of a semi-circular recess 19 which extends outwardly from the inner end of the horizontal portion of the bayonet slot. It will thus be seen that when the plunger 8 is given a rotary motion for a portion of the turn, the pin 12 will travel along the horizontal portion of the bayonet slot and the pressure of the spring 14 will force the yoke 16 against the enlargement 10 and will thereby seat the pin 12 within the recess 19, thereby securing 10 the plunger 8 against accidental rotary disengaging motion.

15 It will be noted that a self filling fountain pen has been provided in which the tube is collapsed throughout its extent during the filling operation and in which extremely simple means have been provided for accomplishing this result. It will also be noted that manipulation of the fountain pen during filling operation may be made 20 by one hand of the operator with ease.

25 It will further be noted that this increased ease of filling in operating the pen is not secured at a sacrifice of security or freedom 30 from inadvertent discharge thereafter. In the construction embodying this invention, positive means have been provided which prevent accidental discharge of the ink from the pen and such means are not complicated or difficult of manipulation or of assembly 35 but are of extremely simple and efficient design.

I claim:

1. A self filling fountain pen comprising a pen carrying portion, a collapsible tube mounted thereon, a cylindrical body surrounding said tube, and means extending outwardly from the top portion of the pen for collapsing said tube, said means arranged 50 to be locked in one position of adjustment, said means adapted to collapse said tube when given a longitudinal motion.

2. A self filling fountain pen comprising a body portion, a collapsible tube mounted 55 therein, an elongated U-shaped spring member having its arms positioned upon opposite sides of said tube, and means extending outwardly from said body portion for causing the simultaneous inward bowing of said spring arms to thereby collapse said tube.

3. A self filling fountain pen comprising a body portion, a collapsible tube mounted 60 therein, an elongated U-shaped spring member having its arms positioned upon opposite sides of said tube, plates mounted upon op-

posite sides of said tube between said tube and said spring arms, and means extending outwardly from said body to simultaneously bow said spring arms and thereby cause said plates to collapse said tube.

70

4. A self filling fountain pen comprising a body, a tube mounted within said body, an elongated U-shaped spring member having its arms positioned upon opposite sides of said tube, plates mounted upon said spring arms and positioned upon opposite sides of said tube, and a plunger for causing simultaneous motion of said plates to collapse said tube.

75

5. A self filling fountain pen comprising a body, a tube mounted within said body, an elongated U-shaped spring member mounted within said body and having its arms positioned upon opposite sides of said tube, plates mounted upon said spring arms and arranged to bear upon opposite sides of said tube, and a plunger projecting from the upper end of said body and arranged to have motion of rotation and translation.

80

6. A self filling fountain pen comprising a cylindrical body portion, a collapsible ink tube mounted therein, an elongated U-shaped spring member having its arms initially bowed inwardly and positioned within said cylindrical body and upon opposite sides of said tube, plates mounted between said arms and said tube and carried by said arms, a cap secured upon the upper end of said bayonet slot, a plunger mounted within said cap and having a pin adapted to travel within said bayonet slot, thereby temporarily locking said plunger in one position, said plunger being adapted to bear upon the yoke portion of said elongated U-shaped spring member and cause the approach of an intermediate portion of said spring arms, thereby causing said plates to collapse said ink tube.

90

7. A self filling fountain pen comprising a body portion, a tube mounted within said body portion, an elongated U-shaped spring member having its arms initially bowed toward each other, and positioned upon opposite sides of said tube, and a plunger adapted to cause said arms to approach each other and collapse said tube, said body portion having a bayonet slot adjacent said plunger with an outwardly extending recess at its outer end and a pin carried by said plunger and adapted to coöperate with said bayonet slot and to be finally seated in locked position within said recess.

100

In testimony whereof I affix my signature in the presence of two witnesses.

PAUL H. QUALMANN.
